UNITED STATES PATENT OFFICE

153,891

DESIGN FOR A WRITING INSTRUMENT OR THE LIKE

Stanley Joseph Meno, Toronto, Ontario, Canada

Application March 12, 1948, Serial No. 145,048

Term of patent 14 years

(Cl. D74—24)

To all whom it may concern:

Be it known that I, Stanley Joseph Meno, a citizen of the Dominion of Canada, residing in the city of Toronto, in the county of York, in the Province of Ontario, have invented a new, original, and ornamental Design for a Writing Instrument or the like, of which the following is a specification, reference being had to the accompanying drawings, forming a part thereof.

In the drawings:

Figure 1 is a front elevational view of a writing instrument or the like, showing the essential features of my design in full lines; and

Figure 2 is a side elevational view of the disclosure in Figure 1.

I claim:

The ornamental design for a writing instrument or the like, substantially as shown and described.

STANLEY JOSEPH MENO.
